UNITED STATES PATENT OFFICE.

WILLIAM BAYLEY, OF SPRINGFIELD, OHIO.

INTERLOCKING JOINT FOR SASH-BARS.

1,136,087.

Specification of Letters Patent. Patented Apr. 20, 1915.

Application filed October 23, 1913. Serial No. 796,813.

To all whom it may concern:

Be it known that I, WILLIAM BAYLEY, citizen of the United States, residing at Springfield, in the county of Clark and State of Ohio, have invented certain new and useful Improvements in Interlocking Joints for Sash-Bars, of which the following is a specification.

My invention relates to metallic window sash and particularly to the interlocking joint for the sash bars thereof.

The object of the invention is to simplify the structure of metallic window sashes as well as the means and mode of interengaging the bars thereof, whereby they will not only be cheapened in construction, but will be more rigid, of maximum strength, economical in manufacture and unlikely to get out of repair.

20 It has heretofore been the custom when joining transverse bars, crossing at an angle one to the other, to cut both of the bars partially through, forming a joint known in joinery at halving, or to distort one of the bars, in order that the other bar may be thrust through such distorted portion. Either of these modes of joining transverse bars greatly weakens the structure. Bars which have been distorted for the introduction of a second bar, can not be returned uniformly to their original shapes. The bending of the engaging portions of such bars, first outward to form an eye of sufficient size to receive the inserted bar, and then back to approximately the original shape to engage the bar inserted therein, greatly weakens the material at the juncture point.

A further object of the present invention is to provide a form of joint in which the 40 marginal portion of the bar will be undisturbed and in which the eye through which the second bar is thrust will be arranged in a longitudinal direction, thereby retaining a maximum amount of metal at the opposite sides of each eye.

A further object of the invention is to provide means for positively locking the engaged bars in their interengaging position.

With the above primary and other incidental objects in view, as will more fully appear in the specification, the invention consists of the features of construction, the parts and combinations thereof and the mode of operation or their equivalents as hereinafter described and set forth in the claims.

Referring to the drawings, Figure 1 is a perspective view of a portion of a metal window sash disclosing a completed interlocking joint forming the subject matter hereof. Figs. 2 and 3 are perspective views of two sash bars to be interengaged one with the other and hereinafter designated for convenience as the needle and eye bars respectively. Fig. 4 is a perspective view of the insert, by which the bars are locked in their interengaged positions. Fig. 5 is a detail perspective view illustrating the initial operation in the formation of the opening of the eye bar. Fig. 6 is a detail perspective view showing the initial step in the interengagement of the bars. Fig. 7 is a perspective view showing the method of locking the bars in their interengaged positions.

Like parts are indicated by similar characters of reference throughout the several views.

In constructing a metal window sash by the method herein described, there are employed a series of eye bars 1, spaced apart in parallel relation and a series of needle bars 2 arranged in transverse angular relation with the eye bars 1 and parallel one with the other. Both the eye bars and needle bars are preferably though not necessarily of a similar T shaped cross section. The head or flange 3 of the bars provides ledges or shoulders extending substantially perpendicular to the webs of the bars to form supports for the glass. To provide uniform supports for the glass, it is desirable that the inner or glass engaging faces of the shoulders or ledges of the respective eye and needle bars be flush one with the other. In order that the finished sash shall be of pleasing appearance, it is desirable that the outer faces of both the head and web portions of the eye and needle bar be flush one with the other. To accomplish these results without materially weakening either of the bars is one of the primary objects of the invention. Both the eye and needle bar are preferably though not necessarily provided with longitudinal beads 4 upon opposite sides of the web portion extending parallel with the flange or head 3 to form intermediate the bead and head a channel for putty or other sealing material.

In preparing the bars for interengagement one with the other, the eye bars 1 are provided with deltoidal openings or slots

5, through which the needle bars hereinafter described may be introduced. The opening or eye 5 is of comparatively small proportion, its longitudinal length being substantially equal to the width of the needle bar, while the transverse width of the eye 5 at its widest point is substantially equal to the width of the transverse head 3 of the needle bar. It is to be noted that the eye 5 being 10 longitudinally disposed in the bar leaves a portion of metal of maximum extent undisturbed at each side thereof. There is no distortion or straining of the adjacent portions of the bar and these parts retain their 15 original shape and alignment. In forming the eye or opening 5, the initial step consists in punching or otherwise forming in the web of the bar two spaced openings comprising a transverse slot 6 and a circular 20 hole 7. The transverse slot 6 is substantially equal in length to the undisturbed portion of the needle bar hereinafter described, while its width is preferably somewhat less than the thickness of the web of 25 the needle bar. After the bar is perforated as shown in Fig. 5, the intermediate deltoidal shaped portion 8 of the material as shown by dotted lines in said figure is removed. This removed portion of the bar is 30 reserved to be subsequently used as a locking insert to secure the needle bar in its adjusted position. There is thus formed the eye or opening as disclosed in Figs. 3 and 6, while the portion removed appears as shown 35 in Fig. 4. The web of the needle bar 2 is provided with a notch or recess 9 sufficiently wide to receive the beads 4 of the eye bar 1. The depth of the notch is substantially equal to the width of the undisturbed portion 40 of the web of the eye bar adjacent to the widest portion of the eye 5. In forming this notch 9, sufficient material is preferably though not necessarily left to form lips 10 at each exterior angle of the recess. In a 45 position in transverse alignment with the recess or notch 9, the head 3 of the needle bar is cut away as shown at 11 for a distance equal to the width of the head of the eye bar. There is thus left between the recess 9 and the recess 11 an undisturbed portion 50 of the web of the needle bar substantially equal to the width of the eye 5 of the eye bar at its widest point. To interlock the bars, the needle bar 2 is inserted through the eye or slot 5 of the eye bar 1 with the head 3 of the needle bar engaging the widest portion of the slot or eye until the notch or recess 9 of the needle bar is in registry with the web of the eye bar and the cut away portion of the head 3 of the needle bar is in registry 60 with the head 3 of the eye bar as is shown in Fig. 6. The needle bar 2 is then rotated throughout a partial revolution causing the separated portion of the head 3 of the needle bar to engage upon opposite sides of the

head of the eye bar and the marginal portion of the web of the eye bar to engage within the notch or recess 6 of the needle bar. This revoluble movement is continued throughout substantially a quarter rotation. 70 The needle and eye bar are thus brought to relatively angular positions with the heads 3 and margins of the web of the respective bars flush one with the other, as shown in Figs. 1 and 7. The bars are thus interlocked 75 one with the other against independent longitudinal or lateral movement. To lock the bars against disengagement by a return rotation of the needle bar, the insert 8 removed in forming the eye or slot 5 is returned to its position within said slot. Inasmuch as the primary slot 6 was made of less width than the thickness of the web of the needle bar the insert 8 will be found to be slightly larger than the remaining portion 80 of the eye or slot 5 after the needle bar has been inserted. The wedge shaped insert, after being slightly filed at 16 to provide clearance, however, is placed in position as shown in Fig. 7 with its apex alined 85 with the web of the eye bar and its base portion resting against the web of the needle bar, whereupon it may be swaged into position in a plane common with the web of the eye bar by means of a tool directed as shown 90 by dotted lines in said Fig. 7. In swaging the insert to its final position, the apex of the insert is crowded longitudinally into the circular perforation 7 which provides clearance for the insert. The wedge or deltoidal 95 shape of the insert permits it to be driven into the remaining opening, where it serves to clamp the needle bar in its adjusted position. Making the initial slot of slightly less width than the thickness of the web of the 100 needle bar insures a tight fit when the insert 8 is replaced in the opening or eye 5. The slight difference in the size of the insert as compared with the remaining opening after 105 the needle bar has been inserted, is sufficient 110 to cause the insert to be held in its adjusted position by the pressure of its edges upon those of the eye or opening without additional fastening means. However to further secure the insert in place, impressions 14 may 115 be made in the metal of the web and the insert across their juncture line as shown in Fig. 1. These impressions may be made by a blow of the hammer or other suitable tool whereby the metal of one member is forced across the juncture line into the edge of the other member. It is obvious that the 120 insert after being replaced in the eye or opening, may be secured by electric or gas welding in a common or well known manner or a rivet 12 may be inserted in the opening 7, the rivet heads upon opposite sides of the web serving to secure the insert in its position. The glass 15 is permanently secured 125 in position by means of a body 13 of putty 130

or other sealing material located in the channel intermediate the bead 4 and the edge of the glass 10 as shown in Fig. 1. The lips 10 of the recesses 9 are bent forward to engage 5 the web of the needle bar after the bars are interengaged.

While the bars 1 and 2 have been herein shown and described as T shaped in cross section, it is obvious that bars of other 10 shapes as I shaped, L shaped or flat bars may be interlocked in the same manner. The only variations necessary for interlocking such different bars, is a difference in the outline of the eye 5 and the proportions 15 of the recesses 7 and 9 to correspond with the cross sectional shapes of the bars. It is likewise obvious that the construction is equally applicable to structures other than window sashes.

20 From the above description it will be apparent that there is thus provided a device of the character described possessing the particular features of advantage before enumerated as desirable but which obviously 25 is susceptible of modification in its form, proportion, detail construction or arrangement of parts, without departing from the principle involved or sacrificing any of its advantages.

30 While in order to comply with the statute, the invention has been described in language more or less specific as to certain structural features, it is to be understood that the invention is not limited to any specific details, 35 but that the means and construction herein described comprise but one mode of putting the invention into effect, and the invention is therefore claimed broadly in any of its possible forms or modifications within the 40 scope of the appended claims.

Having thus described my invention, I claim,

1. In an interlocking joint for bars, two 45 bars arranged angularly one with the other, a deltoidal aperture in one of the bars, the second bar having oppositely disposed marginal recesses and inserted through the aperture of the first bar and engaged therewith by a partial rotation, and a separate wedge shaped insert filling the remaining portion 50 of the aperture after the insertion of the second bar.

2. In an interlocking joint for bars, two 55 bars arranged angularly one with the other, a deltoidal aperture in one of the bars, the second bar having oppositely disposed marginal recesses and inserted through the aperture of the first bar and engaged therewith by a partial rotation, and a separate truncated 60 insert forced into the aperture remaining after the insertion of the second bar.

3. In an interlocking joint for bars, two 65 bars arranged angularly one with the other, one of the bars having a longitudinally dis-

posed aperture formed therein by the removal of a section of material, the second bar having oppositely disposed marginal notches therein thrust through the aperture of the first bar and engaged therewith by a 70 partial rotation, and a separate insert of greater extent than the aperture remaining after the insertion of the second bar forced into the remaining aperture to secure the second bar against removal. 75

4. In an interlocking joint for bars, two bars arranged angularly one with the other, one of the bars being provided with a deltoidal aperture having an enlargement of the opening at its apex, the second bar having oppositely disposed marginal notches being thrust through the aperture of the first bar and engaged therewith by a partial rotation, and a separate deltoidal insert of greater proportions than the aperture remaining after the insertion of the second bar forced into the said remaining aperture for the apex of which the enlargement of the aperture affords clearance. 85

5. In an interlocking joint for bars, two 90 bars arranged angularly one with the other, one of the bars having an aperture therein, the second bar having oppositely disposed marginal notches, said second bar being thrust through the aperture of the first bar 95 and engaged by a partial rotation, a separate insert filling the aperture remaining after the insertion of the second bar, and a shouldered retaining member overhanging simultaneously the margins of the insert and 100 aperture.

6. In an interlocking joint for sash bars, a bar having an aperture therein, a second bar having oppositely disposed marginal notches, said second bar being projected 105 through the aperture of the first bar and interengaged therewith by a partial rotation and a separate locking plate inserted in the aperture remaining after the insertion of the second bar. 110

7. In an interlocking joint for sash bars, a bar having an aperture therein, a second bar having oppositely disposed marginal notches, said second bar being projected through the aperture of the first bar and interengaged therewith by a partial rotation, 115 and a separate locking insert forced into the aperture remaining after the insertion of the second bar substantially equal in extent to the original aperture less a portion of 120 less extent than the cross area of that portion of the second bar engaged within the recess.

8. A bar having an aperture therein, a second bar having oppositely disposed marginal notches, said second bar being projected through the aperture of the first bar and interengaged therewith by a partial rotation, and a separate locking member within the aperture remaining after the insertion 125 130

of the second bar capable of lateral displacement in the plane of the bar.

9. A bar having an aperture therein, a second bar having oppositely disposed marginal notches, said second bar being projected through the first bar and interengaged therewith by a partial rotation, and a separate locking member inserted in the aperture remaining after the insertion of the second

bar so proportioned in relation with the 10 aperture as to normally tend to project into the space occupied by the inserted bar.

In testimony whereof, I have hereunto set my hand this 8th day of October, 1913.

WILLIAM BAYLEY.
